ATTORNEY

UNITED STATES PATENT OFFICE.

HENRY SPENGLER, OF NEW YORK, N. Y.

BOTTLE CAP.

Application filed April 20, 1926. Serial No. 103,201.

The present invention is a closure for bottles and other containers, and the objects of the invention are to provide a cap of simple, inexpensive construction, capable of being easily applied and removed, and which at the same time forms an adequate closure for the container.

The cap disclosed herein is an improvement on the cap described and claimed in my co-pending application No. 693,849, filed Feb. 19, 1924. The present invention provides means for reinforcing and stiffening the spring fingers so that the cap can be formed from relatively light-weight metal.

15 In the drawings:

Fig. 1 is a plan view of a metal strip showing how the caps are punched therefrom.

Fig. 2 is a top plan view of the cap.

Fig. 3 is an elevation of the cap.

20 Fig. 4 is a bottom plan view of the cap.

Fig. 5 is a cross section through the cap.

Fig. 6 is a cross section through a modified form.

25 Fig. 7 is a perspective view of the cap shown in section in Fig. 6.

Fig. 8 is a partial plan view, broken away and showing another modified form of the holding fingers.

30 Fig. 9 is an elevation of still another modification.

Fig. 10 is a section on line 10—10 of Fig. 9.

The cap shown is stamped from suitable spring material, usually spring sheet metal, and is slotted at its periphery to provide the two sets of holding fingers 10 and 11. The fingers 10 are first bent inwardly as shown in Fig. 3 and then the fingers 11 are bent into place. As a result of this procedure the fingers 11 will overlap fingers 10, as indicated at 12 in Fig. 2. The width of the outer fingers 11 can be increased by swaging the edges of said fingers, thereby increasing the amount of overlap.

45 The spring holding fingers are turned inwardly to provide hooks or claws 13 (Fig. 3) to ride over and engage beneath a bead or shoulder on the neck of the bottle or other container to which the cover may be applied.

In order to reinforce the fingers so that the cap can be made from aluminum or other light-weight metal, the ends of the fingers are corrugated or crimped at 14. In the modification shown in Figs. 6 and 7 the fingers are

further strengthened by outwardly projecting corrugations or ribs 15 extending from the flat crown into the bases of the fingers. The flat crown may be reinforced by having an inwardly bulged central portion 16 or an inwardly projecting annular bead 17.

In the modification shown in Fig. 8, the fingers 11 are provided with L-shaped extensions 18 which extend over the adjacent fingers 10 and into corresponding recesses 19. When removing the cap, the ends 20 of the extensions are forced out of engagement with the recesses, permitting expansion of the rim of the cap. The surface of the lower fingers 10 may be raised to the level of the upper fingers as at corrugations 22, to give the cap a relatively smooth feel.

In the embodiment shown in Figs. 9 and 10, the overlapping fingers are provided along the lower rim of the cap with outwardly bulging portions 24. These portions serve to strengthen the fingers and, furthermore, afford a secure finger hold for removing the cap. One of the overlapping fingers may be extended downwardly to present a lever 25, which by affording increased leverage facilitates removal of the cap, the lever being first pulled away slightly from the wall of the container, and then pushed upwardly, when removing the cap.

I claim:

1. In a bottle closure, a cap provided with dependent, inturned spring fingers, yielding reinforcing members overlying said fingers, the ends of said fingers and of said members being crimped and the reinforcing members and fingers being provided with interlocking means.

2. In a bottle closure, a cap provided with angularly extending spring fingers, yielding reinforcing members overlapping said fingers, the sides of said reinforcing members being extended by swaging.

3. In a bottle closure, a cap provided with angularly extending spring fingers, yielding reinforcing members overlapping said fingers, ribs extending into the crown of the cap and into the bases of the fingers, the ends of said fingers and of said members being crimped and the reinforcing members and fingers being provided with interlocking means.

4. In a bottle closure, a cap provided with dependent, inturned spring fingers adapted

to ride over and engage beneath the bead of a bottle neck, yielding reinforcing members overlying said fingers, and outwardly bulging portions pressed into the lower ends of said members and forming finger holds.

5. In a bottle closure, a cap provided with dependent, inturned spring fingers adapted to ride over and engage beneath the bead of a bottle neck, yielding reinforcing members overlying said fingers, one of said members being extended downwardly to form an opening lever and the reinforcing members and

6. In a bottle closure, a cap provided with 15 dependent, inturned spring fingers, adapted to ride over and engage beneath the bead of a bottle neck, yielding reinforcing members overlying said fingers, slots formed in said fingers, and hook-shaped projections formed 20 on said members and extending into said slots.

In testimony whereof I affix my signature.

HENRY SPENGLER.
